UNITED STATES PATENT OFFICE.

JOHN T. PROFFITT, OF ST. DAVID, ARIZONA TERRITORY.

CHIMNEY-COWL.

No. 927,072.

Specification of Letters Patent.

Patented July 6, 1909.

Application filed June 5, 1908. Serial No. 436,841.

To all whom it may concern:

Be it known that I, JOHN T. PROFFITT, a citizen of the United States, residing at St. David, in the county of Cochise, Territory of Arizona, have invented certain new and useful Improvements in Chimney-Cowls; and I do hereby declare the following to be a full, clear, and exact description of the invention, such as will enable others skilled in the art to 10 which it appertains to make and use the same.

The invention relates to a chimney cowl or hood and more particularly to the class of revoluble cowls adapted to discharge the 15 smoke issuing from the chimney in the direction in which the wind is blowing.

The primary object of the invention is the provision of a revolving cowl or hood mounted upon the end of a stove pipe or chimney 20 and rotatably mounted upon a spindle or shaft and having its bearing upon a supporting rib exteriorly of the pipe or chimney.

Another object of the invention is the provision of a chimney cowl or hood revolvably 25 mounted upon the end of a stove pipe or chimney, said cowl or hood having its bearing at the free end of a spindle or shaft vertically disposed and supported centrally in the stove pipe or chimney, and furthermore 30 the said cowl or hood has its lower edge bearing against a bearing rib projecting from the stove pipe or chimney.

With these and other objects in view the invention, for example, consists in the construction, combination and arrangement of parts as will be hereinafter more fully described in detail and as illustrated in the accompanying drawings which disclose the preferred form of embodiment of the invention, 40 however, changes, variations and modifications may be made such as come properly within the scope of the claim hereunto appended without departing from the spirit of the invention.

45 In the drawings:—Figure 1 is a side elevation of the invention. Fig. 2 is a vertical sectional view thereof. Fig. 3 is a side elevation looking from the rear thereof into the open mouth portion of the cowl or hood. 50 Fig. 4 is a transverse sectional view on the line 4—4 of Fig. 3. Fig. 5 is a slight modification of the invention.

Similar reference characters indicate corresponding parts throughout the several views 55 in the drawings.

In the drawings, the numeral 6 designates

a cylindrical stove pipe or chimney within which at the upper end thereof is arranged a supporting frame 7 having cross arms or transverse bars 8 and 9 at the top and bottom respectively, the latter having oppositely disposed right angular ears 10 secured to the stove pipe by rivets 11 while the frame 7 at the opposite side of the pipe is secured by rivets 12 thereto and centrally of the transverse bars 8 and 9 are registering openings 13 through which freely pass a vertically disposed shaft or spindle 14 having at its upper extremity a reduced bearing portion 15 which projects through an opening 16 formed centrally in a transverse bar or arm 17 each end of which is bent on itself downwardly to form a right-angular securing ear 18 which ears are fastened by rivets 19 to a revoluble cowl or hood 20.

75 The hood or cowl 20 comprises a semi-circular body 21 having opposite parallel side extensions 22 and the lower edge of the body 21 and a portion of the side extensions traverses and bears upon an annular bearing rib 23 formed on the stove pipe 6 near the upper open end thereof. The opposite upper edge of the body 21 has a right angular flange 24 in interlocking engagement with a securing flange 25 formed at the outer edge of a 80 flat top 26 which latter has a projecting portion or extension 27 disposed a distance beyond the rear or open mouth portion 28 of the hood or cowl. The open mouth portion 28 of the hood or cowl is held in the direction 85 in which the wind is blowing by a vane 29 secured by rivets 30 to the top 26 of the said cowl or hood.

A distance removed from the transverse bar 17 is a transverse bar or arm 31 having a 90 central opening 32 through which the shaft or spindle 14 passes and which bar or arm is connected to the body 21 by rivets 33 engaging the ears 34 thereof.

95 It is obvious that the hood or cowl 20 in revolving upon the stove pipe 6 has its bearing at the top thereof on the reduced extremity 15 of the spindle and a bearing at its bottom or lower extremity by engaging and traversing the annular bearing rib 23 as the lower edge of the body 21 contacts with said annular bearing rib when the cowl or hood revolves on the spindle so that the latter is considerably relieved of unnecessary strain during the revolving movement of the cowl 100 or hood effected by a strong wind.

105 In Fig. 5 there is shown a slight modifica-

tion and to the side extensions 22 secured by rivets 35 is a bearing strap 36 having engagement with the annular bearing rib 23 on the stove pipe and which strap produces a continuous bearing edge at the lower extremity of the cowl or hood and also prevents the outward spreading of the side extensions 22 of the same. The reduced extremity 15 of the spindle 14 is flared or enlarged as at 37 10 whereby the spindle is prevented from disengagement in the hood and stove pipe or chimney.

What is claimed is—

The combination with a stove pipe having 15 an outwardly projecting annular rib a distance removed from its upper edge, of a frame having centrally perforated transverse bars secured in said pipe, a hood having a vertically disposed semi-circular-shaped wall 20 terminating in spaced parallel side extensions projecting a considerable distance beyond

the circumference of the pipe, said wall being provided with an outwardly projecting flange at its upper edge, a top projecting beyond the straight extensions of said wall and having 25 an inwardly curled marginal end engaging the flange of said wall, the lower edge of said wall adapted to contact with said annular rim, centrally perforated transverse bars secured within said wall, a vertically disposed 30 spindle passing through the perforations contained in said bars and having a reduced upper extremity forming a bearing for the hood at the upper end thereof, and a vane fixed centrally to the top. 35

In testimony whereof, I affix my signature, in presence of two witnesses.

JOHN T. PROFFITT.
